UNITED STATES PATENT OFFICE.

CHARLES F. PYM, OF LYNN, MASSACHUSETTS, ASSIGNOR TO UNITED SHOE MACHINE CORPORATION, OF PATERSON, NEW JERSEY, A CORPORATION OF NEW JERSEY.

UPPER-TIGHTENING DEVICE.

Application filed November 19, 1920. Serial No. 425,123.

To all whom it may concern:

Be it known that I, CHARLES F. PYM, a subject of the King of England, and residing at Lynn, in the county of Essex and State of Massachusetts, have invented certain Improvements in Upper-Tightening Devices, of which the following description, in connection with the accompanying drawings, is a specification, like reference characters on the drawings indicating like parts in the several figures.

This invention relates to tightening devices of the type adapted more especially for closing together the eyeleted edges of turn shoes at second lasting, although it is apparent that in many aspects the invention is not limited to such use.

In the manufacture of turn shoes, it is customary to lace up the shoe tops before putting them on the lasts preparatory to attaching the soles and also before the relasting operation after the soles are attached. The lacing is usually done with twine, an operation involving considerable time and labor and the use of considerable amounts of twine which is afterward cut by the operator and thrown away.

The object of the invention is to provide a small, inexpensive temporary fastening which may be quickly and easily attached to a shoe upper for drawing it tightly on a last with the eyeleted edges together. In the embodiments selected for illustration, a pair of holders having eyelet engaging hooks are mounted for relative movement controlled by curved members which may be in the form of rings which lock the holders in their clamped relation to the eyelets of a shoe. The holders are preferably thin, flat plates and move bodily toward each other about an axis substantially parallel to the instep portion of the shoe. When closed they lie close to the shoe where they cannot interfere with subsequent operations.

In accordance with one embodiment, the rings may also be arranged to provide a mechanical advantage for forcing the holders to their clamped position. In another embodiment, the holders are connected by curved bars on which one of the holders may tilt to bind the holders in clamping position.

These and other features of the invention,

including certain details of construction and combinations of parts, will be set forth in connection with illustrative embodiments of the invention and pointed out in the appended claims.

Referring to the drawings,—

Fig. 1 is a perspective view showing one form of my invention applied to a relasted shoe and also showing a treadle-operated clamp which may be used to force the holders together to cause the opposite eyeleted edges of the upper to approach each other over the last;

Fig. 2 is a perspective view of the tightening device detached;

Fig. 3 is a perspective view of a relasted shoe showing another form of my tightening device applied to it;

Fig. 4 is a perspective view of the device detached;

Fig. 5 is a perspective view of still another form of my invention;

Fig. 6 is a diagrammatic view showing the manner in which the rings act to clamp the eyelet engaging members together.

In the form of my invention shown in Fig. 2, the tightening device consists of two relatively movable holders each comprising a pair of connected plates 10 which may be stamped out of sheet metal and each having pressed out portions 14 and 16 facing each other to form cavities in which are inserted eyelet engaging hooks 18. Each holder with its hooks 18 forms one of a pair of clamping members which engage the shoe eyelets and draw them together over the last. These hooks are each formed of a piece of wire bent back upon itself between the ends to form a shank 20 and two oppositely extending terminal portions 22 which form retaining stops. The pressed out portions 14 and 16 form angular cavities in which fit loosely the shank and terminal stop portions of the eyelet engaging hooks and the cavities are of sufficient extent to enable the hooks 18 to have sliding movement in order to register with eyelets which are differently spaced. To one of the holders are rigidly secured as at 32, curved bars 28 which act as guides for the other holder, the bars passing loosely through openings 34 and having retaining knobs 30 at their ends to prevent separation of the parts.

These bars 28 also act to lock the holders in closed position since the tension on the shoe upper tends to tilt the holders and causes them to bind frictionally against the bars. In Fig. 1 I have shown a shoe 36 mounted on a last and the form of my invention just described applied to the eyelets 38.

In order to draw the holders together, a special form of treadle operated clamp may be used as shown in Fig. 1. It may consist of a hollow sleeve 60 having horizontal ears 62 and 64 which are secured in any desired manner to the table 66. Attached to the sleeve 60 is a lower jaw 68 and above this is mounted a jaw 70 carried on the upper end of a sleeve 74 slidable in the sleeve 60 and treadle operated. In order to raise the jaw 70 after it has been depressed to clamp the holders together, a coiled spring 76 is mounted within the enlargement 72 and bears at its upper end against the adjusting screw 78 and at its lower end against an abutment block 80 mounted on a pin 82 secured to the sleeve 60. The pin 82 and the block 80 are embraced by the sleeve 74, a long slot 84 in the latter sliding past pin 82 and serving to prevent rotation of the clamping jaws with reference to each other. In the lower end of the sleeve 74 is a pin 86 to which are connected rods 88 and 90 actuated by the treadle 94. Any suitable clamp 92 may be used to adjustably connect the rods. When the treadle is released the spring 76 raises the upper jaw 70 and later, when it is desired to release the holders from the shoe, any suitable tool may be inserted between them at the sides opposite the hooks 18, to swing them back into a radial position where they will easily slide along the bars 28.

In the form of tightening device illustrated in Fig. 4, the rings 128 afford a mechanical advantage in forcing the holders toward each other although the treadle operated clamp may be used to aid in this operation. As shown, the holders and the eyelet engaging members may be formed in precisely the same way as described with reference to Fig. 2, but in addition there is provided a bowed spring 24 having slots 26 through which pass the large rings 128, these large rings also passing through suitable apertures 134 in the holders. The ends of the holders are cut away on a curve as indicated at 12 so that the rings may be rotated in the apertures 134 for the purpose of locking the holders in clamping relation as indicated in Fig. 3. These rings act to secure a mechanical advantage in the closing movement of the holders and the manner in which they act will appear from reference to Fig. 6 where the ring 128 is shown passed loosely through apertures 134 in the plates 10. The outer surface of each ring

bears against the points 50 which provide a fulcrum, and the inner surface of the ring bears against the points 48, and, when both rings are rotated, the holders are forced together bodily in a curve to apply equal tension to all the eyelets. When the rings are turned sufficiently around over the ends of the holders, the latter will be locked in position, the spring 24 causing them to engage the rings frictionally. In this position, all of the parts of the device lie close to the shoe and do not interfere with subsequent operations. The spring also aids in separating the holders when the rings are again turned back toward their initial positions.

In the form shown in Fig. 5, the holders and eyelet members are formed in a similar manner but I utilize spring plates 40 attached to the holders as by rivets 44 and through apertures 234 in these plates, I insert the rings 228. The ends of the plates 40 are curved as indicated at 42 and the holders are locked in closed position by swinging the rings around the ends 42 as just described with reference to Figs. 3 and 4.

The operation of my tightening device is believed to be apparent from the above without any more detailed description.

Having thus described my invention, what I claim as new and desire to secure by Letters Patent of the United States is:

1. In a device of the class described, a pair of holders mounted to move bodily toward and from each other in a curve, eyelet engaging members projecting from the holders, and means to guide the holders in their movement.

2. In a device of the class described, a pair of holders shaped to conform to the instep portion of a shoe, eyelet engaging hooks carried by the holders, and means at both ends of the holders for guiding them toward each other to draw together the eyeleted edges of a shoe.

3. In a device of the class described, a pair of clamping members mounted for relative movement, and a pair of rings for forcing the clamping members toward each other with a mechanical advantage.

4. In a device of the class described, a pair of relatively movable holders, a series of eyelet engaging members mounted on each holder, and means to move all the members with the same mechanical advantage to permit the application of equal tension to all the eyelets.

5. In a device of the class described, a pair of relatively movable holders, eyelet engaging members carried by the holders, and a member passed through one of the holders to slide therein and serve as a guide during the relative movement of the holders.

6. In a device of the class described, a

pair of relatively movable holders, eyelet engaging members carried by the holders, and a curved member slidably supporting the holders for relative movement in a curve 5 toward and from each other.

7. In a device of the class described, a pair of relatively movable holders, a series of eyelet engaging members movably mounted on each holder to engage eyelets which are differently spaced, and a curved member slidably supporting the holders for relative movement in a curve toward and from each other. 10

8. In a device of the class described, a pair of relatively movable holders, each holder comprising a pair of plates having expanded portions facing each other, eyelet engaging members mounted in the cavities formed by the expanded portions, and means to 15 guide the holders in their relative movement toward and from each other.

9. In a device of the class described, a pair of relatively movable holders, a series of eyelet engaging members mounted on each holder, and curved members near the ends of the holders arranged to guide the relative movement thereof and to secure the members in clamped relation to the eyelets of a shoe. 20

10. In a device of the class described, a pair of thin, flat holders arranged to move bodily toward and from each other about an axis located substantially parallel to the instep portion of a shoe, eyelet engaging members carried by the holders, and means for 25 forcing the holders toward each other to bring the eyeleted edges of a shoe upper together.

11. In a device of the class described, a pair of holders having cavities formed therein, a series of eyelet engaging members fitting loosely in the cavities to compensate for differently spaced eyelets, and means to secure the members in clamped relation to the eyelets of a shoe. 30

12. In a device of the class described, a pair of holders, each holder having a series of angular cavities, a series of eyelet engaging members each having a shank and a terminal stop for insertion in an angular cav- 45

ity, and means to secure the members in clamped relation to the eyelets of a shoe. 50

13. In a device of the class described, a pair of relatively movable holders, eyelet engaging members carried by the holders, and means to lock the members in clamped relation to the eyelets of a shoe, including a 55 spring which also acts to separate the holders when the locking means is released.

14. In a device of the class described, a pair of relatively movable holders carrying eyelet engaging members, a spring interposed between the holders, and means to lock the holders in closed relation against the pressure of the spring. 60

15. In a device of the class described, a pair of relatively movable holders, a series of eyelet engaging members carried by each holder and rings for locking the members in engagement with the eyelets of a shoe. 65

16. In a device of the class described, a pair of relatively movable holders each having cavities formed therein, a series of eyelet engaging members movably mounted in the cavities to engage eyelets which are differently spaced, and rings slidable through 70 openings in the holders for guiding the 75 holders in their relative movement.

17. In a device of the class described, a pair of relatively movable holders having openings, eyelet engaging members carried by the holders, rings loosely engaging the openings and constructed and arranged to guide the holders in their relative movement and to rotate in the openings to force the 80 holders toward each other to bring the eyelet 85 engaging members into clamping relation to the eyelets.

18. In a device of the class described, a pair of relatively movable holders, eyelet engaging members carried by the holders, means to lock the members in clamped relation to the eyelets of a shoe, and a spring arranged to separate the holders when the locking 90 means is released.

In testimony whereof I have signed my 95 name to this specification.

CHARLES F. PYM.
